MOUNTING FOR SPINNING RINGS AND
THE LIKE

George L. Meyers, Willoughby, and John C. Shutt,
Wickliffe, Ohio, assignors to The Ohio Rubber
Company, Willoughby, Ohio, a corporation of
Ohio

Application August 23, 1946, Serial No. 692,650

6 Claims. (Cl. 57—122)

1

The present improvements, while specifically relating as indicated to spinning ring mountings, i. e. to the provision of improved means for supporting a spinning or twisting ring or ring holder in a ring rail, are not limited to such particular application but may be utilized to secure other forms of "rings" in corresponding openings, as for example to secure window "surrounds" in automobile bodies.

One principal object of the invention is to provide a resilient mounting, i. e. one which will permit a certain amount of yielding on the part of the ring under operating conditions and at the same time act as a dampener to reduce vibration and noise. A further object is to provide a mounting which will permit of the ready placement of a ring in the supporting member without requiring the use of any tool, while at the same time a firm and secure mounting is provided for said ring under operative conditions.

To the accomplishment of the foregoing and related ends, said invention, then, consists of the means hereinafter fully described and particularly pointed out in the claims.

The annexed drawing and the following description set forth in detail certain mechanism embodying the invention, such disclosed means constituting, however, but one of various mechanical forms in which the principle of the invention may be used.

In said annexed drawing:

Fig. 1 is a plan view of a typical spinning ring shown as supported by our present improved mounting in a ring rail;

Fig. 2 is a transverse section of the foregoing, the plane of the section being indicated by the line 2—2, Fig. 1;

Fig. 3 is a sectional view on a larger scale of one portion of such ring and the mounting therefor; and

Fig. 4 is a sectional view similar to Fig. 3 but showing a modification in construction.

The ring rail 1, as shown in Figs. 1 and 2, is of usual construction, consisting of a channel-form member pressed from sheet metal and of any desired length so as to support a series of spinning rings aligned lengthwise thereof. However, a separate support may be provided for the individual rings, the particular form of such support being no part of the present invention. The individual rings 2 are likewise of usual construction, being in the form of an annulus provided on its inner face with one or more circular trackways 3 whereon the spinning or twisting device (not illustrated) is rotatably supported. For the

reception of each such ring 2 the rail is formed with a circular opening 4 of somewhat larger diameter than the exterior diameter of the ring body although the latter may have a radially projecting flange 5 of the same or slightly larger diameter than such opening. In addition, the body of said ring is formed with an encircling groove 6 located in spaced relation below such flange 5.

For the purpose of mounting the ring in the opening in the ring rail a grommet or gasket 7 of special cross-sectional form, as will now be described, is provided, such grommet being composed of resilient material, e. g. of rubber, either natural or synthetic, vulcanized to the desired degree, or of equivalent resilient, compressible, material. This grommet is interposed between the outer face of the ring body and the edge of the opening 4 in the ring rail and constitutes the sole connecting means between the two parts in question. As best shown in Fig. 3, said grommet is formed with an inwardly directed rib 8 that is adapted to seat in the recess 6 in the ring body and with a peripheral groove 9 that is adapted to engage the edge of the opening 4 in the ring rail. While such groove is formed so as to embrace such edge more or less closely, the rib 8 on the grommet in the construction under consideration is of less depth, or cross-sectional area, than recess 6. The latter, it will be noted, is located substantially opposite the edge of the opening which is thus engaged by the peripheral groove on the grommet, but may be slightly displaced and the corresponding edge of the recess in the grommet may be slightly rounded as shown in Fig. 3.

In the assembled condition of the parts the rib or flange 5 on the body of the ring rests on the upper face of the grommet and such ring is additionally held in place relative to the grommet by the engagement between recess 6 therein with the inwardly directed rib 8 on the grommet. Finally, the latter is secured in place by engagement of the peripheral groove in its outer face with the edge of the opening in the ring rail. However, due to the resilient, compressible, character of said grommet, upon forceful movement of the ring in a downward direction axially of such opening a portion of the grommet adjacent rib 8 thereon will be squeezed into the space normally remaining between such rib and the bottom of groove 6 in the ring. This space will be sufficient to accommodate the volume of such displaced material and the latter will be sufficient to permit the grommet to slide past the

edge of opening 4, so that the grommet, together with the ring, to which it is previously attached, may be readily inserted in the ring rail. Conversely, when it is desired to remove the ring, pressure is applied thereto in the opposite direction, whereupon similar displacement of the grommet occurs and the lower portion thereof is folded sufficiently to permit it to snap past the opening in the support. When the ring is thus removed, the grommet may in turn be stretched radially outwardly sufficiently to disengage it from the ring, if desired.

In the modified construction illustrated in Fig. 4 the ring rail 1 and ring 2 are of substantially the same construction as that described above, the only difference being that the peripheral groove 10 in the body of the ring is curved at its bottom instead of being of rectangular cross-section. Likewise, the grommet 11 is of substantially the same construction as gasket 1 except that the rib 12 thereon, which is designed to engage such groove 10, is of substantially the same conformation so as to completely fill the latter. Also the outer face of the grommet in which is formed a groove 13 designed to engage the edge of the opening 4 in the ring rail more closely engages both sides of the latter adjacent such opening than in the case of grommet 1. Finally, said grommet is formed on its inner face immediately below rib 12 with an inwardly directed encircling groove 14.

In the assembled condition of the parts the grommet 11 obviously will function in identically the same way as grommet 1 to support the ring 2 in the opening in the ring rail. When it is desired to remove the ring, pressure is applied thereto as before, and the portion of the grommet adjacent such last-mentioned groove 14 will be compressed and displaced to a sufficient extent to permit the groove 13 in such grommet to be disengaged from the edge of opening 4 in the ring rail. Conversely, by corresponding compression and displacement of such portion of the grommet the latter may be forced downwardly through such opening until the groove in question is again brought into engagement with such edge.

It will be understood that in the operation both of removing and thus inserting the ring in place in its mounting the grommet will remain attached thereto by engagement of rib 12 on the grommet with groove 10 in the ring. It will also be noted that the lower outer face of said grommet is beveled or inclined outwardly, which serves to facilitate placement of the ring, with the grommet carried thereby, in the opening in the supporting member.

As previously stated, in both of the two illustrative forms of our improved spinning ring mounting the grommet constitutes the sole connecting means between the ring rail or equivalent supporting member, i. e. there is nowhere any metal-to-metal contact between the parts in question. At the same time, owing to the unique form and construction of the grommet, removal and replacement of the ring may be readily accomplished without detracting from the security with which it is held in place in the assembled condition of parts.

As likewise previously remarked, the ring rail 1 is merely illustrative of a similar supporting member, in an opening in which it is desired to mount a ring. Similarly the term "ring" as used herein is to be understood as connoting any equivalent member which it may be desired to mount

in such an opening. Thus said ring, and the opening wherein it is mounted, may be of other than circular form and be designed for other use than to support a spinning or twisting device.

Finally, it should be noted that depending on the relative extent axially of the edge of the opening in the supporting member and of the juxtaposed outer face of the ring the disposition of grooves and ribs on the grommet may be reversed.

Other modes of applying the principle of our invention may be employed instead of the one explained, change being made as regards the mechanism herein disclosed, provided the means stated by any of the following claims or the equivalent of such stated means be employed.

We therefore particularly point out and distinctly claim as our invention:

1. In mechanism of the character described, 20 the combination with a support having an opening and a ring adapted to be mounted in such opening, of a grommet of resilient material interposed between said ring and the edge of such opening, said ring being formed with an encircling recess and said grommet with an inwardly directed rib adapted to seat in such recess and with a peripheral groove adapted to engage such edge.

2. In mechanism of the character described, 30 the combination with a support having an opening and a ring adapted to be mounted in such opening, of a grommet of resilient material interposed between said ring and the edge of such openings, said ring being formed with an encircling recess and said grommet with an inwardly 35 directed rib adapted to seat in such recess and with a peripheral groove substantially opposite said rib adapted to engage such edge.

3. In mechanism of the character described, 40 the combination with a support having an opening and a ring adapted to be mounted in such opening, of a grommet of resilient material interposed between said ring and the edge of such opening, an encircling groove being formed in one of the juxtaposed faces of such opening and ring and said grommet being formed with a radially projecting rib adapted to seat in such recess and with an oppositely directed groove adapted to engage the other such juxtaposed face.

4. In mechanism of the character described, 50 the combination with a support having an opening and a ring adapted to be mounted in such opening, of a grommet of resilient material interposed between said ring and the edge of such opening and constituting the sole connecting means between said parts, said ring being formed with an encircling recess and said grommet with an inwardly directed rib adapted to seat in such recess, the outer face of said grommet below such 60 rib being beveled and such rib not entirely filling such recess to permit forcible insertion of said ring and grommet in such opening by deformation of said grommet.

5. In mechanism of the character described, 65 the combination with a support having an opening and a ring adapted to be mounted in such opening, of a grommet of resilient material interposed between said ring and the edge of such opening, said grommet having interlocking engagement with both said ring and said support and a circumferentially extending portion of a peripheral surface of said grommet opposed to one of said ring and support being spaced therefrom to permit forcible insertion of said ring and

5 grommet in such opening by deformation of said grommet.

6. In mechanism of the character described, the combination with a support having an opening and a ring adapted to be mounted in such opening, of a grommet of resilient material interposed between said ring and the edge of such opening, said grommet having interlocking engagement with both said ring and said support and constituting the sole connecting means between said parts, a circumferentially extending portion of the inner peripheral surface of said grommet opposed to said ring being spaced there-

from to permit forcible insertion of said ring and grommet in such opening by deformation of said grommet.
